Primary Examiner — Ruth McInroy*(74) Attorney, Agent, or Firm* — McGarry Bair PC(57) **CLAIM**

The ornamental design for a V stick vac foot, as shown and described.

DESCRIPTION

FIG. 1 is a front perspective view of a V stick vac foot which embodies our design;

FIG. 2 is a front view thereof;

FIG. 3 is a rear view thereof;

FIG. 4 is a left side view thereof;

FIG. 5 is a right side view thereof; and,

FIG. 6 is a top view thereof.

The bottom view is unornamented.

The details shown in broken lines form no part of the claimed design.
